(57) **CLAIM**

The ornamental design for a three-wheeled vehicle, as shown and described.

DESCRIPTION

FIG. 1 is a front, perspective view of the three-wheeled vehicle;

FIG. 2 is a front view of the three-wheeled vehicle;

FIG. 3 is a right side view of the three-wheeled vehicle;

FIG. 4 is a rear view of the three-wheeled vehicle; and,

FIG. 5 is a top view of the three-wheeled vehicle.

The broken lines in the drawings, including the tread and inner hubs of the rear wheels, depict unclaimed environmental subject matter.
